UNITED STATES PATENT OFFICE.

JOHN F. A. HOORT, OF NEW YORK, N. Y., ASSIGNOR TO THE EAST ROCKFORD MANTEL COMPANY, OF ROCKFORD, ILLINOIS.

DESIGN FOR A MANTEL.

SPECIFICATION forming part of Design No. 24,284, dated May 7, 1895.

Application filed April 4, 1895. Serial No. 544,500. Term of patent 3½ years.

To all whom it may concern:

Be it known that I, JOHN F. A. HOORT, a citizen of the United States, residing at New York, in the county of New York and State 5 of New York, have invented and produced a new and original Design for Mantels; and I do hereby declare the following to be a full, clear, and exact description of the same, reference being had to the accompanying drawing, forming a part thereof.

The figure of the accompanying drawing is an isometric view of the new design for mantels. Its leading feature consists in the design for a mantel the mantel shelf situated 15 between two columns that extend from bases formed in columnar mantel supports to an entablature extending across a panel frame surmounting the mantel shelf.

Numeral 1 denotes the mantel, 2 the columns and 3 the entablature constituting a 20 shelf parallel to and longer than the mantel shelf proper.

The entablature and the mantel are each supported by brackets 4 and in the latter case the brackets support festoons 5. 25

What I claim is—

The design for a mantel as herein shown and described.

In testimony whereof I affix my signature in presence of two witnesses.

JOHN F. A. HOORT.
